182,303

FLOOR TOOL OR SIMILAR ARTICLE FOR A VACUUM CLEANER

Robert J. Reading, Stratford, and William J. Cook, Trumbull, Conn., assignors to General Electric Company, a corporation of New York

Application November 21, 1956, Serial No. 43,867

Term of patent 14 years

(Cl. D9—2)

Fig. 3.

Fig. 4.

Fig. 5.

Fig. 1 is a top plan view of a floor tool or similar article for a vacuum cleaner embodying our new design;

Fig. 2 is a front elevational view thereof;

Fig. 3 is a perspective view thereof;

Fig. 4 is a rear elevational view thereof;

Fig. 5 is a side elevational view thereof with the coupling tube omitted for convenience of illustration only.

The dominant features of the design reside in the portions shown in full lines.

We claim:

The ornamental design for a floor tool or similar article for a vacuum cleaner, substantially as shown and described.
